CLAIM

The ornamental design for a toothbrush caddy, as shown and described.

DESCRIPTION

FIG. 1 is a front elevational view of a toothbrush caddy showing my new design;

FIG. 2 is a right side elevational view thereof;

FIG. 3 is a top plan view thereof;

FIG. 4 is a top, front, and right side isometric view thereof;

FIG. 5 is a front elevational view of the insert for the toothbrush caddy, with the exterior portion of the caddy omitted for clarity of illustration;

FIG. 6 is a right side elevational view thereof;

FIG. 7 is a top plan view thereof; and,

FIG. 8 is a top, front, and right side isometric view thereof.

The broken-line disclosure is understood to be for illustrative purposes only and forms no part of the claimed design.
